Primary Examiner — Mark Goodwin(74) *Attorney, Agent, or Firm* — SAIDMAN DesignLaw Group(57) **CLAIM**

The ornamental design for a tray, as shown and described.

DESCRIPTION

FIG. 1 is a top view of a tray showing my new design; FIG. 2 is a perspective view thereof; FIG. 3 is a front thereof, the rear being a mirror image; and, FIG. 4 is a bottom view thereof.
The broken line showing is for the purpose of illustrating portions of the tray and forms no part of the claimed design.
